CLAIM

The ornamental design for a triple display alarm clock, as shown.

DESCRIPTION

FIG. 1 is a top, front, and left side perspective view of a triple display alarm clock showing my new design;

FIG. 2 is a front elevation view of my new design, which shows the front elevation view of the front-most elongated button;

FIG. 3 is a rear elevation view of my new design, which shows the rear elevation view of the four spaced buttons having circular top surfaces;

FIG. 4 is a left side elevation view of my new design, which shows the left side view of the left, long side of the left side curved button;

FIG. 5 is a right side elevation view of my new design, which shows the right side view of the right, long side of the right side curved button;

FIG. 6 is a top view of my new design; and,

FIG. 7 is a bottom view of my new design.
